UMBRELLA MARKER

Irvin I. Hearing, Hammonton, N. J.

Application December 8, 1938, Serial No. 244,701

2 Claims. (Cl. 40—10)

The invention relates to an article marker and more especially to an umbrella marker.

The primary object of the invention is the provision of a marker of this character, wherein an umbrella, parasol or the like as well as other articles can be identified in that an identification is applied and in the use thereof upon an umbrella, parasol or the like, it will be in such a position to be hidden from view, particularly when such article is folded and in this manner minimizes the possibility of the loss or misappropriation of such article.

Another object of the invention is the provision of a marker of this character, wherein the same in its entirety is novel, particularly in the assembly and the application to the article, not in the least interfering with the handling of the umbrella, parasol or the like, and affords an attached identification medium for such article.

A further object of the invention is the provision of a marker of this character, wherein its construction permits of separable attachment to an article and when attached constitutes an identification as to the owner or user of the umbrella, parasol or the like, particularly when such article is placed in a rack or other holder while not in use.

A still further object of the invention is the provision of a marker of this character, wherein the same, when worn upon the article, will be unaffected by weather elements and does not detract from the appearance of the article wearing the same, being practically concealed from view, and affords identification thereof.

A still further object of the invention is the provision of a marker of this character, which is simple in its construction, thoroughly reliable and efficient in operation, easy of application to and separation from the article, durable, neat in its appearance, susceptible of being changed from one article to another and inexpensive to manufacture.

With these and other objects in view, the invention consists in the features of construction, combination and arrangement of parts as will be hereinafter more fully described, illustrated in the accompanying drawing, which discloses the preferred and modified forms of embodiment of the invention and pointed out in the claims hereunto appended.

In the accompanying drawing:

Figure 1 is a fragmentary sectional view through an umbrella showing the marker con-

structed in accordance with the invention applied.

Figure 2 is a view similar to Figure 1 looking toward the other side of the marker.

Figure 3 is a fragmentary perspective view of 5 the marker.

Figure 4 is a sectional view taken on the line 4—4 of Figure 1.

Figure 5 is a plan view of one blank of the 10 marker.

Figure 6 is a plan view of another blank 10 thereof.

Figure 7 is a plan view of the identifying card employed with the marker.

Figure 7a is a plan view of a holding strap 15 employed with the marker.

Figure 8 is a transparent cover piece for the 20 card.

Similar reference characters indicate corresponding parts throughout the several views in 20 the drawing.

Referring to the drawing in detail, A designates generally a portion of a rib employed in the build of the cover frame of an umbrella, parasol or the like and B a portion of the cover, 25 which is fastened at 10 to the rib at the reduced ball terminal 11 of the latter in the conventional manner. Fitted to the rib A is a marker denoted generally at C and constructed in accordance with the invention. 30

The marker in the preferred embodiment thereof, as illustrated in Figures 1 to 8, inclusive, of the drawing, comprises a foldable section 12 having a crease line 13 transversely thereof at its intermediate portion, being disposed crosswise of the said section so as to permit the folding thereof to effect a back 14 and a front 15 uniformly sized with respect to each other and in matched relation when folded. The front 15 is provided with an elongated slot effecting a window 16 for visibility of identifying indicia 17 upon a card 18 placed between the back 14 and the front 15 on the folding of the section 12. The card 18 has disposed over its front indicia-carrying side a transparent piece 45 19 allowing the exposure therethrough of the indicia 17 through the window 16 for visibility. 40

The card 18 with the transparent piece 19 is disposed forwardly of a section 20 with the transparent piece 19 in front of the latter and 50 this section 20 is within the fold of the section 12. The section 20 is preferably made from sheet metal while the section 12 is made from leather or other fibrous material. The card is made from sheet cardboard and it is preferable 55

to have the transparent piece 19 made from Celluloid.

The section 20, when within the folded section 12, which latter is saddled over the rib A between it and the cover B in the position as shown in Figure 1 of the drawing, has provided at opposite ends and along one side edge bendable tongues 21 and 22, respectively, certain of these being folded rearwardly and overlie the folded portion 14, which is the back of the section 12, while the remainder of said tongues are folded forwardly and upwardly to overlie the front 15 of the section 12 and in this manner the marker is assembled attached to the rib A of the umbrella, parasol or the like.

The other side edge of the section 20 has a foldable flap 23 carrying a tongue 24 and underlying this flap 23 is a holding strap 25 secured in any suitable manner in place, it having a slotted end 26 adapted to be slipped over the ball terminal end 11 of the rib A. The tongue on the flap 23, when the latter is folded, is inserted in a slot 27 therefor provided in the front 15 of the section 12 and in this manner the marker is completely assembled and in attached relation to the rib A of the umbrella, parasol or the like.

What is claimed is:

1. In combination with an umbrella having a rib, and a cover tacked thereto, a marker comprising a folded body saddling said rib adjacent

to the tucked point of the cover therewith and forming a front and back of uniform size with respect to each other in matched relation one to another, said front having a slot, an identification card between the front and back and partially exposed by said slot, a section fitting the body in rear of the said card and having a folded flap next to the fold side of said body provided with a tongue engaged in said body, and tongues on the section and reversely folded over the front and back of said body for unitary assembly of the card, body and section. 5

2. In combination with an umbrella having a rib, and a cover tacked thereto, a marker comprising a folded body saddling said rib adjacent 15 to the tucked point of the cover therewith and forming a front and back of uniform size with respect to each other in matched relation one to another, said front having a slot, an identification card between the front and back and partially exposed by said slot, a section fitting the body in rear of the said card and having a folded flap next to the fold side of said body provided with a tongue engaged in said body, and tongues 20 on the section and reversely folded over the front and back of said body for unitary assembly of the card, body and section, and a holding strap secured between the body and said section and looped onto the rib. 25
